HIRAM C. WILLIAMS, OF UTICA, AND FRANCIS B. HARRINGTON, OF ALBANY, NEW YORK,
ASSIGNORS TO GENERAL ELECTRIC COMPANY, A CORPORATION OF NEW YORK.

CONTROLLING APPARATUS FOR RAILWAY APPLIANCES.

No. 892,636.

Specification of Letters Patent.

Patented July 7, 1908.

Application filed November 4, 1907. Serial No. 400,646.

To all whom it may concern:

Be it known that we, HIRAM C. WILLIAMS and FRANCIS B. HARRINGTON, citizens of the United States, residing, respectively, at Utica, county of Oneida, State of New York, and at Albany, county of Albany, State of New York, have invented certain new and useful Improvements in Controlling Apparatus for Railway Appliances, of which the following 10 is a specification.

Our invention relates to the control of interlocked levers for controlling railway appliances, and its object is to provide a time-limit device for insuring a certain interval 15 between the operation of certain of the levers. Such a time-interval is especially desirable between the operation of levers controlling respectively a signal and a switch, in order that the switch may not be thrown without 20 giving sufficient warning to an approaching train, by properly setting the signal a certain length of time before the switch is thrown.

Our invention consists in providing a time-limit circuit-closer operated by one of the 25 levers, and comprising a receptacle containing a conducting fluid and having two chambers joined by a restricted opening, so that the flow of fluid from one chamber to the other is retarded, and circuit-terminals in 30 one chamber in circuit with an electromagnet controlling a lock for another of the levers.

Our invention will best be understood by reference to the accompanying drawings, in which.

35 Figure 1 shows diagrammatically a pair of interlocked levers provided with time-limit controlling means arranged in accordance with our invention; Fig. 2 shows a front elevation, partly in cross-section, of the time- 40 limit circuit-closer; and Fig. 3 shows a side-elevation of the same.

In Fig. 1, A and B represent a pair of levers interlocked in the usual manner by suitable apparatus, indicated diagrammatically at C. D represents a signal controlled by the lever A, and E a switch controlled by the lever B. F represents a time-limit circuit-closer, which is operatively connected to the lever A by a rack a, which is moved by 50 the lever and a pinion f on the circuit-closer. The circuit-closer is rotatably mounted so that when lever A is shifted, raising or lowering the rack a, the circuit-closer is rotated. This circuit-closer F is constructed, as will 55 be hereinafter described, so that a certain

interval elapses between this movement and the closing of its circuit. G represents an electromagnet in circuit with the device F controlling a lock for the lever B. H represents the usual track-relay, which may control the slot mechanism J of the lever A, indicated diagrammatically at signal D, and also controls the lock-magnet G jointly with the device F, so that the lever B cannot be thrown when a train occupies the track-section to which the relay H is connected.

In Fig. 1, the switch E is thrown for the main track, and the signal D stands at clear. If the operator desires to throw the switch for a siding, he must first throw the lever A 70 so as to set the signal D at danger, in order that the lever B may be unlocked by the interlocking mechanism C. After the lever A is thrown to set the signal D at danger, the lever B cannot immediately be shifted, because the circuit-closer F does not immediately close its circuit when the lever A is shifted. A certain time elapses before the circuit of the magnet G is closed so as to cause the magnet to unlock the lever B, and 80 this time-interval either enables a train to stop at the signal D, or, if it is already passing the signal, to de-energize the relay H, so as to prevent the magnet G from being energized, and to protect itself from having lever 85 B thrown beneath its wheels.

The construction of the time-limit circuit-closer is shown in Figs. 2 and 3. The casing, or fitting, F of the circuit-closer is rotatably mounted, and contains a receptacle K, 90 adapted to contain mercury. This receptacle, which may be secured within the casing by cement, as indicated in Fig. 2, has two chambers, which are joined by a large opening or spout k, and a restricted opening k'. 95 When the receptacle K is rotated clockwise through ninety degrees from the position shown in Fig. 2, the mercury passes from the left-hand chamber through the opening or spout k into the right-hand chamber. This 100 opening is large enough so that the transfer of the mercury is practically instantaneous. This is the movement of the receptacle which occurs when lever A is shifted to clear the signal. When the lever A is returned to set 105 the signal at danger, the receptacle is returned to the position shown in Fig. 2, in which position the mercury slowly flows back from the right-hand to the left-hand receptacle through the restricted opening k'. This 110

opening is so small that a considerable time elapses before sufficient mercury can flow into the left-hand receptacle to connect the circuit-terminals L. These circuit-terminals 5 may be connected to the opposite halves of the casing or fitting F if these halves are insulated as indicated by the insulating ring M of Fig. 3, and if the outer bearing for the fitting is also insulated from the supporting 10 bracket, as indicated at m in Figs. 2 and 3. By this construction the necessity of employing sliding contacts or flexible leads is avoided, and binding-posts O O may be employed for connecting the device in circuit. 15 Certain of the structural details of the circuit-closer, above described, we do not claim as our invention, the scope of which is pointed out in the annexed claims.

What we claim as new, and desire to secure 20 by Letters Patent of the United States, is,—

1. In combination with a plurality of interlocked levers for controlling railway appliances, a time-limit circuit-closer comprising a receptacle containing a conducting fluid 25 and having two chambers joined by a restricted opening through which said fluid passes when said receptacle is moved from one of its positions to the other, and circuit-terminals in one of said chambers, operative 30 connections between one of said levers and said circuit-closer whereby said receptacle is moved when said lever is shifted, an electromagnet in circuit with said circuit-closer, and means controlled by said electromagnet for 35 locking another of said levers.

2. In combination with a plurality of interlocked levers for controlling railway appliances, a time-limit circuit-closer comprising a receptacle containing a conducting 40 fluid and having two chambers joined by a large opening and a restricted opening through

which respectively the fluid passes when said receptacle is moved in opposite directions, and circuit-terminals in one of said chambers, operative connections between one of said levers 45 and said circuit-closer whereby said receptacle is moved when said lever is shifted, an electromagnet in circuit with said circuit-closer, and means controlled by said electromagnet for locking another of said levers. 50

3. In combination with a plurality of interlocked levers for controlling railway appliances, a rotatably mounted fitting operatively connected to one of said levers, a receptacle adapted to contain mercury carried by 55 said fitting and having two chambers joined by a restricted passage, and circuit-terminals in one of said chambers, an electromagnet in circuit with said terminals, and means controlled by said electromagnet for locking another of said levers.

4. In combination with a plurality of interlocked levers for controlling railway appliances, a rotatably mounted fitting operatively connected to one of said levers, a receptacle adapted to contain mercury carried by 65 said fitting and having two chambers joined by a large and a restricted passage, and circuit-terminals in one of said chambers, an electromagnet in circuit with said terminals, 70 and means controlled by said electromagnet for locking another of said levers.

In witness whereof, HIRAM C. WILLIAMS has hereunto set his hand this first day of November, 1907, and FRANCIS B. HARRINGTON 75 has hereunto set his hand this first day of November, 1907.

HIRAM C. WILLIAMS.
FRANCIS B. HARRINGTON.
